CLAIM

The ornamental design for a combined rail and post component for a frame system with couplers, as shown and described.

DESCRIPTION

FIG. 1 is an isometric view of the combined rail and post component for a frame system with couplers of the design of the present invention;

FIG. 2 is a left side elevation view thereof the right side, the top, and the bottom being identical thereto; and,

FIG. 3 is a front elevation view, the rear being identical thereto.
